UNITED STATES PATENT OFFICE.

GEORG ENGELHARDT, OF CASSEL, AND CARL FRIEDRICH FÖLSCH, OF WERNIGERODE-ON-THE-HARZ, GERMANY.

LAST.

No. 807,917.

Specification of Letters Patent.

Patented Dec. 19, 1905.

Application filed February 18, 1905. Serial No. 246,258.

To all whom it may concern:

Be it known that we, GEORG ENGELHARDT, manufacturer, a resident of Cassel, and CARL FRIEDRICH FÖLSCH, manufacturer, a resident 5 of Wernigerode-on-the-Harz, Kingdom of Prussia, Germany, subjects of the German Emperor, have invented a new and Improved Last, of which the following is a full, clear, and exact description.

10 The object of the invention is to provide a new and improved last having a hinged toe portion to permit it to be set at different angles to the main portion and to the walking-line of the foot to insure the production of an 15 accurate foot-covering, such as shoes, boots, stockings, and the like.

The invention consists of novel features and parts, as will be more fully described herein-after and then pointed out in the claims.

20 A practical embodiment of the invention is represented in the accompanying drawing, forming a part of this specification, in which the figure is a plan view of a last having its toe portion hinged at one side to permit of 25 swinging the toe portion sidewise to the desired angular position relative to the main portion.

The shoe-last illustrated in the drawing consists of a main portion *i*, including a heel, 30 and a toe portion *f*, connected by a hinge *e* with the said main portion *i* at the inner side of the last, so as to allow of swinging the toe portion *f* sidewise into a desired angular position relative to the main portion *i*, as plainly 35 indicated in dotted lines in the drawing, the different positions being marked with the letters A, B, C, and D. A series of four lasts A, B, C, and D can thus be obtained by this one last. On the toe portion *f* is pivoted a 40 graduated arm *g*, having an elongated slot *g'*, through which extends a screw *h*, screwing in the main portion *i*, so that when the toe portion *f* has been adjusted sidewise to the

desired position then it is fastened in place by screwing up the screw *h*. The hinge *e* is 45 located at or near the beginning of the big toe, so that when the toe portion *f* is swung sidewise the adjustment is made relative to the beginning point of the big toe, so as to obtain a proper relative position between the 50 toe portion *f* and the main portion *i*.

From the foregoing it will be seen that for each number of a last a toe-portion adjustment is had to obtain a correct angular position of the big toe relative with rest of the 55 foot, it being understood that for a certain size foot a last is selected which corresponds as to the size foot, and by means of the additional adjustment of the toe portion relative to the main portion a last is had which corresponds both as to size and shape of the 60 wearer's foot.

Having thus described our invention, we claim as new and desire to secure by Letters Patent—

65 1. A shoe-last, comprising a main portion, and a toe portion hinged to the main portion on the inner side, at a point opposite which the base of the great toe comes.

2. A shoe-last, comprising a main portion, 70 a toe portion hinged to the main portion on the inner side at a point opposite which the base of the great toe comes, and means for locking the toe portion to the main portion.

In testimony whereof we have signed our 75 names to this specification in the presence of two subscribing witnesses.

GEORG ENGELHARDT.

CARL FRIEDRICH FÖLSCH.

Witnesses to the signature of Engelhardt:

GEO. H. SETHS,

WILH. DEMPWOOD.
